UNITED STATES PATENT OFFICE.

FRED J. DUNCAN, OF LUDLOW FALLS, OHIO, ASSIGNOR TO DUNCAN BROS. AND WRAY COMPANY, OF LUDLOW FALLS, OHIO, A COPARTNERSHIP.

FLOOR-SCRAPER.

1,115,517.

Specification of Letters Patent.

Patented Nov. 3, 1914.

Application filed October 26, 1912. Serial No. 727,858.

To all whom it may concern:

Be it known that I, FRED J. DUNCAN, a citizen of the United States, residing at Ludlow Falls, in the county of Miami and State of Ohio, have invented certain new and useful Improvements in Floor-Scrapers, of which the following is a specification, reference being had therein to the accompanying drawing.

10 This invention relates to floor scrapers and the object of the invention is to provide a manually operated wheeled scraper which will be very simple in its construction and highly efficient in its operation; to provide a 15 scraper of this kind which can be adjusted to give a draw cut at different angles and to cut close to the walls; and further, to provide such a scraper with an operating handle which can be adjusted to either pull or push 20 the scraper.

It is also an object of the invention to provide means for utilizing a curved blade in connection with a scraper of this kind.

In the accompanying drawings, Figure 1 25 is a top, plan view of a scraper embodying my invention; Fig. 2 is a longitudinal, sectional view taken centrally through such a scraper; Fig. 3 is a section on the line $\alpha-\alpha$ of Fig. 2 and looking in the direction of the 30 arrows; and Fig. 4 is a detail view of the blade.

In these drawings I have illustrated one embodiment of my invention and have shown the same as comprising a truck or wheeled 35 support on which is mounted a blade, preferably curved about a substantially vertical axis and capable of adjustment about both a horizontal axis and a vertical axis relatively to said supporting wheels and have provided a handle for manipulating the device 40 either by pulling or pushing. The particular embodiment of the invention which is here shown is, of course, chosen for the purpose of illustration only and it will be understood that the various details of construction 45 can be widely varied from the forms here shown.

In the form of the device here illustrated the truck comprises wheels 1 mounted on a 50 transverse axle 2 which, in turn, is mounted

on a frame 3 having at its upper end a socket 4 to receive one end of a vertical stud or pivot pin 5 which is fixed against movement relatively to said socket by a set screw 6. Pivotedly mounted on that portion of the 55 stud 5 which projects above the frame 3 is a frame 7 having at one end downwardly and forwardly projecting arms 8 on which is mounted a blade holder 9. Preferably the blade holder is adjustable about a horizontal 60 axis to enable the angle of the blade to be regulated. This horizontal axis is shown as arranged close to the floor and, as here shown, the lower ends of the arms 8 are provided with apertures to receive pivot pins 65 10 adapted to enter sockets 11 in the adjacent portions of the blade holder 9. This holder may be of any suitable construction but is preferably designed for holding a blade 70 in a curved position. To this end it comprises two clamping members curved about a substantially vertical axis, it being understood that this axis varies with relation to a vertical line as the holder is adjusted about its horizontal axis. The inner member of 75 the holder, which is indicated at 12, has the bearings 11 formed in the lower part thereof and extends upward to a point a considerable distance above the blade. The outer member, which is indicated at 13, fits against 80 the lower portion of the inner member 12 and the two parts are adapted to receive between them a blade 14 which is held in position by screws or bolts 15 mounted in the two members of the holder and extending 85 through slots 16 and the blade 14. The blade may be of any suitable kind but as a straight blade is much easier to sharpen and keep in good working condition than is a curved blade I prefer to employ a flat 90 straight blade of thin metal which, when clamped in position between the two members of the blade holder will be bent into a curved position and maintained in this position during the operation of the scraper. In 95 order to give a better scraping edge to the blade the cutting edge thereof is, after being ground, turned forward or away from the bevel slightly, as indicated at 17. By forming such an edge on a straight blade and 100

then bending the blade this forwardly turned edge is braced against the cutting action and is rendered more durable than a corresponding edge on a straight blade. The cutting edge of the blade is bowed upwardly or in other words is convexed as clearly shown in Fig. 4 of the drawings. The adjustment of the blade holder about its horizontal axis is preferably controlled by a bolt 18 extending 5 through the inner member 12 of the blade holder at a point above the horizontal axis about which the holder is adjustable and also through an apertured lug 19 depending from the frame 7 and arranged between the arms 10 15 8. A spring 20 confined between the lug 19 and the inner member 12 of the blade holder tends to move the holder toward a vertical position and is of sufficient strength to resist the force exerted upon the holder by the cutting 20 action during the operation of the scraper. The bolt 18 may be provided with a hand wheel or knob 21 and also has a nut 22 mounted thereon and arranged between ribs 23 on the rear of the lug 19 which hold 25 the nut against turning. To adjust the blade holder in either direction pressure is exerted upon the upper portion of the member 12 to compress the spring and the bolt is then turned in one direction or the other to secure 30 the desired adjustment.

The purpose of mounting a curved blade on a truck is three-fold: In the first instance it matters not at what angle the blade is positioned, there is always a lead-portion 35 and a straight portion to said blade; in the second instance, by adjusting the blade about the horizontal axis the width of the cut is regulated; and, in the third instance, all jumping or chattering of the machine is 40 avoided. Practice has demonstrated that when a straight blade is employed and is adjusted in a plane at right angles to the line of movement, much jumping and chattering is occasioned, and when the straight 45 blade is adjusted at an angle to the line of movement this jumping or chattering is reduced but not eliminated.

From the foregoing it will be observed that when the curved blade is set in a plane 50 at substantially right angles to the line of movement, both ends of the blade will constitute lead portions while the central portion of said blade will constitute a straight portion. In this position of the blade the 55 entire cutting edge is in a position to scrape the floor. Should this blade be adjusted about its vertical axis, that end of the blade which extends in the direction of the line of movement constitutes the lead portion of 60 the blade, and the remaining or rear portion of said blade constitutes the straight cutting portion. When this blade is adjusted about its horizontal axis, regardless of its position about its vertical axis, the amount of work

done by said blade, or in other words the 65 amount of actual cutting edge, will depend upon the vertical angle to which the blade is adjusted. By providing the blade with a convex cutting edge it may be set at an inclination to the floor and still engage the 70 floor throughout its length. When the blade is in a vertical plane only the central portion of the blade is performing its function and when the blade is tilted forwardly more of the cutting edge will be brought 75 into play as will be readily understood.

Rigidly mounted on the upper end of the stud 5, which projects above the frame 7, is a supplemental frame 24 having mounted at its forward end a pawl or locking device 25 80 adapted to enter the spaces between teeth 26 arranged on the frame 7 near one end thereof and thus control the adjustment of the frame and the blade holder carried thereby about a vertical axis with relation to the 85 truck or supporting wheels. The pawl is here shown as held in its position between the teeth by means of a spring 27. An operating handle 28 is connected with the frame 7 for manipulating the scraper and 90 is preferably mounted on the supplemental frame 24. As here shown it is pivotally connected to lugs 29 projecting upwardly from the opposite sides of the supplemental frame. A brace bar or link 30 is pivotally 95 connected at one end to one end of the supplemental frame 24 and is pivotally connected at its other ends to a collar 31 adjustably mounted on the handle 28. By adjusting the collar along the handle the height at which the 100 handle is supported may be regulated. Further, by moving the collar to a point near the lower end of the handle the latter can be swung across its pivotal center and into the position shown in Fig. 2 which enables the 105 scraper to be pushed instead of pulled. A rod 32 may be connected with the pawl 25 and extended upward along the handle 28 into the position in which it can readily be manipulated by the operator to release the 100 pawl when he desires to adjust the frame relatively to the supporting wheels.

The operation of the device will be readily understood from the foregoing description and it will be apparent that the blade 115 can be readily adjusted about a horizontal axis to cause it to engage the floor at the desired angle. This adjustment when had in combination with the curved blade enables a shearing cut of the desired width and 120 angle to be had and these features, together with the forwardly turned cutting edge of the blade provides a very efficient scraper. Further, it will be apparent that by adjusting the blade holder about a vertical 125 axis with relation to the supporting wheels the horizontal angle of the cut can be regulated and the edge of the cutter can be

caused to project beyond the line of the supporting wheels to enable the floor to be scraped close to the edge of a wall or the like.

5 While I have shown and described one embodiment of my invention it will be understood that the same has been chosen for the purposes of illustration and that I do not desire to be limited to the details of 10 construction shown and described, for obvious modifications will occur to a person skilled in the art. For example, I have shown the supporting wheels connected one with the other to form a truck but obviously 15 they may be connected with the frame or blade holder in any manner which will permit the latter to be adjusted about a vertical axis relatively thereto.

Having thus fully described my invention, what I claim as new and desire to secure by Letters Patent, is:—

1. In a floor scraper, the combination, with a frame, and wheels supporting the same, of a blade carried by said frame, 25 curved about a substantially vertical axis and adjustable relatively to said frame about a horizontal axis.

2. In a floor scraper, the combination, with a frame, and wheels supporting the 30 same, of a blade carried by said frame and adjustable relatively thereto about a horizontal axis, said blade having a convex cutting edge and being curved about a substantially vertical axis.

35 3. In a floor scraper, the combination with a truck, of a blade mounted on said truck to swing about a vertical axis and curved about a substantially vertical axis.

4. In a floor scraper, the combination 40 with a truck, of a blade mounted on said truck to swing about a horizontal axis and curved about a substantially vertical axis, said blade being formed with a convex cutting edge.

45 5. In a floor scraper, the combination with a truck, of a blade mounted on said truck to swing about both a substantially vertical axis and a horizontal axis, and curved about a substantially vertical axis.

50 6. In a floor scraper, the combination with a truck, of a blade mounted on said truck to swing about both a substantially vertical axis and a horizontal axis, and curved about a substantially vertical axis, 55 said blade being formed with a convex cutting edge, the edge being turned in the direction of its cut.

7. In a scraper of the character described, the combination, with a truck, a 60 frame mounted on said truck, and a blade carried by said frame, of a handle pivotally mounted on said frame and movable into operative positions on either side of the vertical plane of its pivotal center, and a brace

bar adjustably connected to said handle and 65 said frame and arranged to brace said handle in each of its operative positions.

8. In a scraper of the character described, the combination, with a truck, a stud rigidly secured thereto, a frame pivotally mounted on said stud, and a supplemental frame rigidly secured to said stud above said frame, of means for locking said supplemental frame in adjusted positions relatively to said main frame, and a blade 75 holder mounted on said frame.

9. In a scraper of the character described, the combination, with a truck, a stud rigidly secured thereto, a frame pivotally mounted on said stud, and a supplemental frame rigidly secured to said stud above said frame, of means for locking said supplemental frame in adjusted positions relatively to said main frame comprising a handle mounted on said supplemental 80 frame, a locking device mounted on said supplemental frame, and an operating member connected with said locking device and extending along said handle.

10. In a scraper of the character described, the combination with a truck, of a main frame pivotally mounted on said truck to swing in a horizontal plane, and a supplemental frame rigidly secured to said truck above the main frame, of a rack connected 95 with said main frame, and a locking device carried by the supplemental frame for engaging the rack to lock the main frame in its adjusted position relative to the truck.

11. In a scraper of the character described, the combination with a truck, of a main frame pivotally mounted on said truck to swing in a horizontal plane, and a supplemental frame rigidly secured to said truck above the main frame, of a rack connected 105 with said main frame, a spring actuated dog pivotally mounted on the supplemental frame for engaging the rack to lock the main frame in its adjusted position relative to the truck, and means for manually 110 releasing said dog.

12. In a scraper of the character described, the combination with a truck, of a main frame pivotally mounted on said truck to swing in a horizontal plane, and a supplemental frame rigidly secured to said truck above the main frame, of a rack connected 115 with said main frame, a spring actuated dog pivotally mounted on the supplemental frame for engaging the rack to lock 120 the main frame in its adjusted position relative to the truck, a handle mounted on said supplemental frame and an operating member connected with said dog and extending along the handle.

13. In a scraper, a wheeled truck, a frame mounted on said truck for movement about a vertical axis and having forwardly and

downwardly extending arms, a blade holder supported on said arms, the lower portion of said blade holder being pivotally mounted on the lower ends of said arms to move about a horizontal axis, and means for securing said frame and said blade holder in adjusted positions.

In testimony whereof I affix my signature in presence of two witnesses.
